BUMPER EXTENSION

George W. Walker, Bloomfield Hills, Mich., assignor to Ford Motor Company, Dearborn, Mich., a corporation of Delaware

Application August 6, 1958, Serial No. 52,075

Term of patent 7 years

(Cl. D14—6)

Fig. 1 is a side elevation on a reduced scale of a bumper extension, showing my new design in use. The portion of an automobile shown in broken lines is for the purpose of illustration only;

Fig. 2 is an enlarged side elevation of the bumper extension;

Fig. 3 is a plan view of the bumper extension;

Fig. 4 is a front elevational view of the bumper extension;

Fig. 5 is a sectional view taken substantially through the line 5—5 of Fig. 2 looking in the direction of the arrows; and

Fig. 6 is a fragmentary sectional view taken substantially through the line 6—6 of Fig. 2 looking in the direction of the arrow.

I claim:

The ornamental design for a bumper extension, substantially as shown and described.
